UNITED STATES PATENT OFFICE.

OSCAR C. McCORMICK, OF CLEVELAND HEIGHTS, OHIO; MAUDE W. McCORMICK ADMINISTRATRIX OF SAID OSCAR C. McCORMICK, DECEASED.

HOLLOW-CLAY STRUCTURAL UNIT.

Application filed August 1, 1921, Serial No. 488,763. Renewed October 23, 1925.

The present improved structural unit is on the order of a hollow block and will be preferably formed of clay, although any plastic material capable of being formed by an extrusion process may be utilized. The object of the present invention is to so form the faces of building blocks or tile of the type referred to that the mortar joints will not extend entirely across the juxtaposed faces of blocks lying in successive courses. On the contrary air spaces are provided entirely separating the mortar that is exposed on the inner faces of the wall from that of the outer face. As a result the tendency for water or moisture to pass from the outer to the inner face of the mortar joint is practically eliminated and plaster applied to the inner face of the wall will not be discolored or show such joints. At the same time, by reason of the additional air spaces provided, the wall is correspondingly insulated against the passage of heat or cold.

To the accomplishment of the foregoing and related ends, said invention, then, consists of the means hereinafter fully described and particularly pointed out in the claim, the annexed drawing and the following description setting forth in detail certain mechanism embodying the invention, such disclosed means constituting, however, but one of various mechanical forms in which the principle of the invention may be used.

In said annexed drawing:—

Fig. 1 is a perspective view of a hollow block or tile embodying my improved construction, such block being of full wall width; Fig. 2 is a view similar to Fig. 1, but illustrating a half width block; Fig. 3 is a transverse section through two blocks of the construction of Fig. 1 superposed as in a wall; Fig. 4 is a view similar to that of Fig. 3, but illustrating the narrower block shown in Fig. 2 superposed in a wall; and Fig. 5 is a broken side elevation of several courses of my improved block as laid in a wall.

In the case of both forms of the block illustrated in Figs. 1 and 2, respectively, the vertical and longitudinal dimensions are the same and correspond with established standards in block manufacture; while in the case of such first form the block is of full wall width, such width corresponding with the longitudinal dimension just referred to, and

in the case of the form illustrated in Fig. 2 such width is just one-half of such longitudinal dimension, or one-half the width of the wall. In both cases the block is of rectangular form save for certain corrugations, as will be presently described.

Thus in the form of block A, illustrated in Fig. 1, it will be observed that the top and bottom walls belly inwardly from lines removed approximately one-third the total width of the block from the respective sides of the latter so as to form shallow longitudinally extending depressions or grooves 1. These grooves are bounded on their lateral edges by ribs 2, constituting mortar stops, and the remaining portion of the face in question lying without such stops is on a slightly lower level and formed with mortar-retaining grooves or channels 3. For the purpose of reinforcement the interior of the block, instead of being entirely hollow is formed with two longitudinally extending walls or partitions 4 that are preferably disposed in alignment with the mortar stops 2; while one or both of the side faces of the block may be provided with corrugations or scorings 5 adapted to interlock with a plaster coating if applied to such face upon assembly of the block into a wall, the corrugations 5 being shown in the drawing on one side only of the block.

In thus assembling the block the courses are laid in the usual fashion, as illustrated in Fig. 5, but the mortar being confined to the spaces between the stops 2 and the respective sides of the block, the two opposed depressions 1 will leave a longitudinally extending air chamber throughout the length of the course, as shown in Fig. 3. It thus becomes impossible for the mortar joint to sweat through and discolor the plaster on the inner face of the wall, while the additional air chamber thus provided further insulates the wall as previously pointed out.

In the case of the narrower block B, shown in Figs. 2 and 4, the longitudinally extending grooves or depressions 7 in the top and bottom walls of the block are narrower, but they are bounded by mortar stops 8 just as before, and in other respects the construction of the block is identical with that of the wider block A, save for the fact that a single interior wall or partition 9 will here provide adequate reinforcement. As shown in the transverse sectional view of Fig. 4, the result

when the narrower block is assembled into a wall is the provision of a longitudinally extending air chamber in the joint between successive courses that effectually separates the inner and outer portions of the mortar joint as in the first construction.

My improved block presents no special difficulties in manufacture, but may be made just as expeditiously and cheaply as ordinary rectangular building block or tile, while the laying up of the wall is, if anything, facilitated. In particular it should be noted that a considerably smaller quantity of mortar is required for the joints between courses, and in a wall of any size the saving in material thus accomplished is a very important factor, as need not be further pointed out.

A much more important saving, however, is that due to the increased strength or load bearing capacity of my improved design of block. Thus it has been found by actual compression tests that a block of such design made of fire clay containing approximately 15 percent less material by weight than a selected shale hollow block will sustain a load at least 50 percent greater.

Other forms may be employed embodying the features of my invention instead of those here explained, change being made in the form or construction, provided the elements 30 stated by the following claim or the equivalent of such stated elements be employed.

I therefore particularly point out and distinctly claim as my invention:—

A structural unit of the character described, comprising a hollow block formed with a longitudinally extending opening and having its top and bottom surfaces provided with centrally located longitudinal grooves, longitudinally extending flat ribs bounding 40 the lateral edges of said grooves, said ribs being raised from said surfaces and adapted to form mortar stops, and two longitudinally extending reinforcing partitions in approximate alignment with said ribs on the top and bottom surfaces of the block providing lateral openings on either side of said longitudinally extending central opening and strengthening said unit adjacent its longitudinal side faces.

Signed by me, this 29th day of July, 1921.
OSCAR C. McCORMICK.
